TELEVISION ANTENNA

James Goumas, Perth Amboy, N. J.

Application November 25, 1949, Serial No. 6,256

Term of patent 7 years

(Cl. D26—14)

To all whom it may concern:

Be it known that I, James Goumas, a citizen of the United States of America, residing at Perth Amboy in the county of Middlesex and State of New Jersey, have invented a new, original, and ornamental Design for a Television Antenna, of which the following is a specification, reference being had to the accompanying drawing, forming a part thereof.

In the drawings:

Figure 1 is a top plan view of a television antenna showing my new design;

Figure 2 is a side elevational view; and

Figure 3 is a front elevational view thereof.

I claim:

The ornamental design for a television antenna, as shown.

JAMES GOUMAS.
